COMBINATION RADIATOR CAP AND MOTOMETER HOLDER

Filed April 18, 1921

Patented Apr. 2, 1929.

UNITED STATES PATENT OFFICE.

DAVID W. BLANC, OF CHICAGO, ILLINOIS, ASSIGNOR, BY MESNE ASSIGNMENTS, TO THE KINGSLEY-MILLER COMPANY, OF CHICAGO, ILLINOIS, A CORPORATION OF ILLINOIS.

COMBINATION RADIATOR CAP AND MOTOMETER HOLDER.

Application filed April 18, 1921. Serial No. 462,271.

My invention relates generally to radiators for automobiles, and more particularly to caps for the radiator inlets, and it consists in the combination, constructions and arrangements herein described and claimed.

An object of my invention is to provide a radiator cap that is adapted to be locked in adjusted position on the inlet of a radiator.

A further object of my invention is to provide a device of the character described that is adapted for engagement with a temperature responsive mechanism of the "motometer" type, whereby the latter is maintained in a desired position on the cap and cannot be displaced readily.

A further object of my invention is to provide a radiator cap that is adapted to be moved instantly into either closed or open position with respect to the inlet of a radiator and is provided with means for maintaining the cap normally in closed position.

A further object of my invention is to provide a device of the character described that can be applied to a radiator of an ordinary construction without any extensive change, if any, being required in the usual construction of the latter.

A further object of my invention is to provide a device of the character described that is thoroughly effective for the purpose intended and practical commercially.

Other objects and advantages will appear in the following specification, and the novel features of the invention will be particularly pointed out in the appended claims.

My invention is illustrated in the accompanying drawings forming part of this application, in which—

Figure 1 is a central vertical section through the device, showing the use and application thereof,

Figure 2 is a side elevation of the device, a fragmentary portion of a "motometer" supported thereby being shown, and

Figure 3 is a top plan view of the device, showing a lid portion thereof in open position.

Referring now to the drawings, 1 denotes a portion of a radiator having a tubular inlet 2 threaded interiorly at 3. A radiator cap embodying my invention comprises a tubular body portion 4 having an exteriorly threaded reduced stem portion 5 adapted to be screwed

into the interiorly threaded inlet 2. The body portion 4 is formed with an interiorly 55 extending annular rib 6 and with an upstanding annular shoulder 7 intermediate its inner and outer walls, thereby defining an inner socket 8 and an outer socket 9 that is 60 concentric with the inner socket 8.

A lid or cover portion 10 of the cap is formed with an inwardly extending annular flange 11 at its lower end adapted to overlie the upstanding shoulder 7 and defining a depending annular shoulder 12 that is adapted 65 to the outer socket 9, as best seen in Figure 1. The cover 10 has a pair of spaced apart integral lugs 13—13 extending laterally thereof and arranged to straddle a cooperating lateral lug 14 that is integral with the body portion 70 4. The lugs 13—13 are fixedly secured to the lug 14 by a pintle 15 so that the cover 10 may be swung about the pintle 15 into open position, as illustrated in Figure 3. The ends of the pintle 15 are upset so that the cover 10 75 cannot be detached from the body portion 4 without the use of great force or heavy tools. Oppositely extending handle members 16—16 are provided as a convenient means for moving the cover 10 with respect to the body portion 4. The body portion 4 is formed with an integral extension 17 that is reduced at 18 and is diametrically opposed to the lug 14. A latch 19, which is substantially U-shaped, has the arms thereof arranged to straddle a 85 lug 20. The arms of the U-shaped latch are secured to the lug 20 by a pin 21 or the like so that the latch may be swung into engagement with the reduced portion 18 of the lug extension 17 and the web of the latch will frictionally engage with the reduced portion 18 to 90 normally maintain the cover 10 in closed position with respect to the body portion 4, as best seen in Figure 2.

The body portion 4 is locked in adjusted 95 position with respect to the radiator inlet 2 by means of a key 22 that is projected into aligned keyways 23 and 24 in the contiguous walls of the stem portion 5 and the tubular inlet 2. The keyway 24 continues into an opening 25 through the body portion 4 so that the key 24 may be driven into place from the interior of the latter.

From the foregoing description of the various parts of the device, the operation thereof may be readily understood. It is fre-

quently desirable to attach a suitable temperature responsive device to the radiator for indicating the thermal condition of the engine in the automobile to which the device is applied. In the drawings, I have shown a device of the "motometer" type and have indicated the same at 26. The "motometer" 26 has a threaded shank 27 screwed into a threaded opening 28 in the cover 10 so that a flange 29 rests upon the cover. The shank 27 depends below the cover 10 into the interior of the body portion. A lock washer 30 and a nut 31 placed on the threaded shank 27 tends to maintain the "motometer" in place. It has been found in service that the vibration of the vehicle to which the device is applied will cause the nut 31 to be displaced and the "motometers" are frequently lost. Furthermore, the loss of the "motometers" is frequently due to theft, since the nut 31 may be readily removed. In order to prevent the loss of the "motometer", I provide a substantially dish shaped spring member 32 that has an inwardly offset portion 33 and an outwardly extending flange 34 at its upper end. The spring member 32 is formed with a central opening 35 adapted to receive the end portion of the shank 27. It is obvious that when the spring member 32 is applied to the cover 10 by springing the same into the position illustrated in Figure 1, so that the flange 34 overlies the upper wall of the shoulder 11 and the offset portion 33 presses outwardly against the inner wall of the annular rib 11 that the spring locking member 32 cannot be readily removed from the interior of the cover 10 and consequently removal of the nut 31 from the shank 27 is precluded.

One of the principal advantages of the device is derived from the fact that the cover 10 may be swung into open position instantly to permit the filling of the radiator 1 in an ordinary manner and that the cover 10 is normally maintained in closed position by the latching means described.

I claim:

1. A device of the type described comprising a radiator cap adapted to be secured to the inlet of a radiator, a cover for said cap, said cover having an opening therein adapted to receive the shank of a motometer, and having an annular shoulder adjacent to its open end, and a closure disposed on said shoulder and being adapted to prevent access to the motometer locking means.
2. A device of the type described comprising a radiator cap adapted to be secured to the inlet of a radiator, a cover for said cap, said cover having an opening therein adapted to receive the shank of a motometer, and having an annular shoulder adjacent to its open end, and a closure consisting of but a single piece and having an outwardly extending flange adapted to engage with the shoul-

der for preventing access to the motometer locking means.

3. A device of the type described comprising a radiator cap adapted to be secured to the inlet of a radiator, a cover for said cap, said cover having an opening therein adapted to receive the shank of a motometer, and having an annular shoulder adjacent to its open end, and a spring closure consisting of but a single piece and having an outwardly extending flange adapted to engage with the shoulder for preventing access to the motometer locking means.

4. A device of the type described comprising a radiator cap adapted to be locked in place to an inlet tube of a radiator, a hinged cover for said cap, said cover having an opening therein adapted to receive the shank of a motometer lock and having an annular shoulder disposed adjacent to the open end of said cover, and a resilient cup-shaped closure adapted to engage with the inner wall of said shoulder and having outwardly extending flanges adapted to engage with the sides of said shoulder, whereby the closure prevents access to the motometer locking means, the inner flange of said closure preventing the removal of the closure when once assembled to the cover.

5. A device of the type described comprising an annular hollow member adapted to be connected to a radiator, a movable cover for said member, retaining means securing the cover against theft, said cover having an opening therein adapted to receive the shank of a motometer with locking means therefor on the inside of the cover, an annular engaging portion on the interior of the cover, and a member disposed on said engaging portion whereby access to the motometer locking means is prevented.

6. A device of the type described comprising a movable cover for the filling opening of a radiator, said cover having an opening therein adapted to receive the shank of a motometer with locking means therefor on the inside of the cover, an annular portion on the interior of the cover, and an annular member disposed on said portion whereby access to the motometer locking means is prevented.

7. A device of the type described comprising an annular hollow member adapted to be connected to a radiator, a movable cover for said member, retaining means securing the cover against theft, said cover having an opening therein adapted to receive the shank of a motometer with locking means therefor on the inside of the cover, an annular portion on the interior of the cover, and an annular member disposed on said portion whereby access to the motometer locking means is prevented.
